[57] CLAIM

The ornamental design for a toy car, as shown and described.

DESCRIPTION

FIG. 1 is a front perspective view of a toy car showing my new design.

FIG. 2 is a right side plan view thereof. The left side plan view is a mirror image of FIG. 2 and thus is not further illustrated.

FIG. 3 is a front plan view thereof.

FIG. 4 is a top plan view thereof.

FIG. 5 is a rear plan view thereof; and,

FIG. 6 is a bottom view thereof.
